UNITED STATES PATENT OFFICE.

SUMNER A. BEMIS, OF SPRINGFIELD, MASSACHUSETTS, AND LOUIS PFINGST,
OF NEW YORK, N. Y.

CABLE-RAILWAY SYSTEM.

SPECIFICATION forming part of Letters Patent No. 388,812, dated September 4, 1888.

Application filed May 21, 1888. Serial No. 274,582. (No model.)

To all whom it may concern:

Be it known that we, SUMNER A. BEMIS and LOUIS PFINGST, citizens of the United States, residing, respectively, at Springfield, county 5 of Hampden, and State of Massachusetts, and in the city, county, and State of New York, have invented new and useful Improvements in Cable-Railway Systems, of which the following is a specification.

10 The present invention relates to improved railways for cable-impelled cars, in which a continuous underground conduit for the cable is combined with the track-rails; and the invention consists in the combination and construction of parts, all as will hereinafter more fully appear, and be particularly pointed out in the claims.

Reference is to be had to the accompanying sheets of drawings, in which similar characters of reference indicate corresponding parts 20 in all the views, and in which—

Figure 1 is a plan view of a portion of the railway-structure; and Fig. 2 an end or front elevation thereof, certain of the continuous 25 longitudinally-extending parts being shown in vertical cross-section. Fig. 3 is a horizontal section through the yokes and the conduit shell-sections supported thereon, taken at the plane indicated by line 6 6, Fig. 2.

30 In the drawings, A A represent the car-wheel rails, and B one of the transverse yokes, on a series of which yokes, disposed at suitable intervals, the said rails A and the parts forming the cable-conduit are supported.

35 Each yoke B consists of a vertical web-wall, a, provided with upper and lower flanges, b c, to give the desired width of bearing-surface for the rest thereon of the parts hereinafter mentioned and for its rest on and in the ground.

40 The edges of said yoke are preferably downwardly-converging, and are ribbed, as at d, for strength, as desired, and may also be provided with rib-bounded apertures e, the said ribs and apertures permitting a better retention 45 of the yoke in the ground. The web-wall a is at its upper central portion cut out in U form, as at g, Fig. 2, the edge of said cut-out part being provided with right-angled flanges or ribs i at each side, as particularly seen in

50 Fig. 2, and between the vertical web-walls a of two properly aligned and distanced

yokes is extended a section of the conduit-shell D, of suitable metal or material—as, for instance, wrought-iron or boiler-plate iron or steel—the ends of said shell-section abutting 55 against the face of the web-wall a, and said shell is curved into U shape to conform to the curve of the under and outer surface of said flanges i, being riveted thereto, as seen at 8, and the edges h of the conduit-shell extend, preferably, above the upper surface of the yoke.

The longitudinal L-shaped paving-rails E E lie over the upwardly-extended edges h of said shell, being grooved longitudinally therefor, as 65 at k, and said paving-rails extend inwardly beyond said grooves, and also outwardly therefrom, as at l, forming bottom flange-rests thereon for their support upon the yokes, being secured thereto, as indicated at m, by bolts 70 and nuts. The bottoms of said rails E are longitudinally ribbed, as at n, either continuously or at intervals, and said ribs fit into correspondingly located grooves o in the top of the yoke.

75

The vertical portions p of the paving-rails have on their inner sides horizontal longitudinal ledges q, on which the lower laterally-extended ends r of the slot-rails F rest, said slot-rails being vertically extended to a height, 80 preferably above the top of the paving-rails, and are inwardly flanged, as at s, the edges of said flanges being when the said rails F are in place separated the distance of and form the walls of the continuous slot t, through 85 which the grip may pass, to engage the cable within the U-shaped conduit and travel. Each slot-rail is also provided with an outwardly-extending flange, u, which lies over the top edge of the paving-rail, the top of which 90 flange u is in a coincident downwardly and outwardly inclining plane with the top of the flange s, forming a water-shed. Between the inside of the vertical portion p of each paving-rail and the opposing vertical face of the 95 slot-rail F are blocks or beams G, of wood or other similar slightly-compressible material, and bolts w are passed horizontally through the thickness of the vertical portions of the paving-rails and slot-rails and through the interposed yielding material, thereby firmly 100 clamping and confining the said parts. India-

rubber in any of its elastic compounds may in some instances advantageously constitute the yielding interposing material.

The track-rails A rest in suitable chairs 5 formed on or attached to the top of the yoke at their outer portions.

Brace-rods M are provided at suitable intervals extending between the track-rails, and the paving-rails being bolted thereto in any 10 suitable manner, and tend to hold same in their proper positions and relations, and the horizontal parallel disposition of the paving-rails is made positive and constant by the interlocking of the ribs n thereon with the grooves 15 o in the top of the yoke, and said paving-rails and the yokes immovably attached form the structure from which the other parts are supported and held in their proper positions.

As will be seen in Fig. 2, the flanges i are 20 shown as extending from the upper end portions of the U-shaped shell D to and ending at a little distance from the median line of the shell, as at 40, so that an unobstructed space is left in the bottom of the conduit at its inside 25 as desirable for various purposes, such as to permit of an effective sweeping or clearing of the conduit.

The yoke B is preferably cast in two sections, as seen at each side of the line 30, Fig. 30 2, a flange-rib, 31, at the abutting portion of each section being formed thereon, through which the bolts 32 are passed for uniting said sections as one. The two-part formation of the yoke possesses important advantages, of 35 which may be noted that an economy of labor is thereby secured; that the half-sections may be cast more nearly perfect than when the yoke is integrally cast; that, should the yoke become broken at one side portion, such portion simply 40 may be replaced, the other being left intact; and that in reaching adjacent gas, water, sewer, or other conduits, for repairs, &c., it may be found only necessary to remove one side of the yoke, the traffic at such time not 45 being necessarily interfered with.

Brackets N may be integrally formed on the yokes either at their edges, as shown, or disposed within the apertures e for the support of a conduit, P, for inclosing electrical 50 ductors.

The edges of the conduit-shell D, extending above the plane of the top of the yoke and into the longitudinal recess k in the paving-rail, afford increased means for maintaining 55 the said shell D immovably in place and against warping and prevent the entrance thereto of dirt, &c., from under the said paving-rail, and the relative formation and arrangement of the slot and paving-rails with 60 the interposed thickness of compressible material G performs a similar dirt-excluding service, and also enables, due to the compressible nature of said interposed material, a nice adjustment of the slot-rails on the supporting paving-rails, so that the slot t may be kept of 65 uniform width.

The dotted lines Q indicate the grade or

paving plane, and it will be noticed that all the bolts for adjusting the slot-rails are near such grade surface and easily reached.

70

Having thus described our invention, what we claim, and desire to secure by Letters Patent, is—

1. The combination, with transverse yokes or frames having U-shaped openings, and the 75 U-formed longitudinal shell-sections D, supported in and secured to said yokes, with their edges extended above the surface thereof, of the longitudinal rails E, provided with the longitudinal grooves k, resting on said yokes 80 and by their said grooves engaging said extended shell-section edges, substantially as set forth.

2. The combination, with the transverse yokes or frames having U-shaped openings, 85 and the U-formed longitudinal shell-sections D, supported in and secured to said yokes, of the longitudinal rails E E, supported on and secured to said yokes at each side of the said openings, and provided with the ledges q, and 90 the slot-rails having the flanges r resting on said ledges and bolted to said rails, substantially as described.

3. In a cable railway, the combination, 95 with the longitudinal conduit-shell continuously open at its upper side, and the longitudinal paving-rails E E, extending along each side of the said conduit-opening, of the slot-rails F F, arranged inside of and parallel with said paving-rails, the yielding material 100 between said paving and slot rails, and the bolts for confining said rails, substantially as and for the purpose described.

4. In a cable railway, the combination, 105 with the longitudinal conduit-shell continuously open at its upper side, and the longitudinal paving-rails E E, extending along each side of the conduit-opening, each provided on their inner sides with the ledges q, of the slot rails F F, provided with the lower 110 outwardly-projecting flanges, r, resting on said ledges, and the upper inwardly-projecting flanges, s, the yielding material G between said slot and paving rails, and bolts for confining said rails, substantially as and for 115 the purpose described.

5. The combination, with the yokes or frames having central U-shaped openings, and the flanges i, arranged at the borders of said openings, with spaces 40 at the median 120 line thereof, of the shell-sections D, extending between said yoke-frames and conformed and riveted to the outer sides of said flanges, substantially as described.

6. The combination, with the yokes or 125 frames having U-shaped openings and provided at their upper sides with the flanges b, having the grooves o, and the shell-sections D, supported in and secured to said yokes, with their edges h extended above the surface 130 thereof, of the longitudinal paving-rails bolted to said flanges b, having the ribs n, entering said grooves o, and the grooves k, lying over said shell-edges h, and the adjustable slot-rails

F F, attached to said paving-rails, substantially as and for the purposes described.

7. A yoke or frame having the opening at its upper central portion, the conduit-shell sections supported therein, the paving-rails E E, supported on and secured to the upper side of said yoke, the slot-rails F F, and interposed compressible material G, secured to said paving-rails, of the track-rails A A, supported

and secured on the outer ends of said yokes, to and the brace-rods M, between and engaging said track and paving rails, substantially as and for the purpose described.
